HOISTING APPARATUS

David A. Wallace, Grosse Pointe Farms, Mich.,
assignor to Walco, Inc., Detroit, Mich., a corpora-
tion of Michigan

Application November 4, 1948, Serial No. 58,219

13 Claims. (Cl. 254—89)

1

This invention relates to improved hoisting apparatus and is an improvement in hoisting apparatus of the character set forth in my copending applications Serial Nos. 15,827, filed March 19, 1948, and 34,772, filed June 23, 1948.

More specifically the invention relates to improvements in hoisting apparatus which is particularly adapted for hoisting vehicles.

In my abovementioned applications there is disclosed a pair of selectively, simultaneously and independently operable hoisting units which are adapted to be drivingly operated by a single continuous screw member, each unit being provided with a releasable nut member that may be selectively engaged with and disengaged from the screw. While apparatus embodying such construction has been found to operate satisfactorily, dependable releasable nut devices are expensive, difficult to construct and have a relatively short life as compared to nut members which are permanently in threaded connection with a screw.

One of the main objects of this invention is to provide a pair of permanently, threadedly engaged screw and nut assemblies in hoisting apparatus of this character which may be simultaneously actuated to respectively raise and lower a pair of hoisting units in unison with each other.

Another object of the invention is to provide a releasable clutch element between the screws of a pair of hoisting units of this character which may be selectively engaged to operate both hoisting units simultaneously or disengaged to accommodate operation of only one of said hoisting units.

Another object of the invention is to provide simplified and improved power driving mechanism which may be utilized to simultaneously operate both hoisting units and to operate only said one of said units.

A still further object of the invention is to provide an electrical control circuit for such power driving mechanism in which is included a pair of limit switch devices, one for interrupting the operation of the power driving mechanism when the boom members of the hoisting units are in predetermined upper and lower positions, respectively.

An additional object of the invention is to provide control apparatus for engaging and disengaging the clutch between the respective screws of the hoisting units and which also serves to hold the limit switch device that limits downward movement of the boom members, against interfering with the operation of the power driving mechanism when the clutch is disengaged so as

2

to allow the power driving mechanism to be utilized in shift said one of the hoisting units bodily relative to the other unit and to raise and lower the said one hoisting unit while the other remains in its lowermost position.

An illustrative embodiment of the invention is shown in the accompanying drawings, in which

Fig. 1 is a perspective view of vehicle hoisting apparatus embodying the invention.

Fig. 2 is a transverse sectional view taken on line 2—2 of Fig. 1.

Fig. 3 is a fragmentary longitudinal sectional view taken on line 3—3 of Fig. 1.

Fig. 4 is a fragmentary plan view of the central portion of the hoisting apparatus shown in Fig. 1, illustrating the respective hoisting units in their lowered positions.

Fig. 5 is a transverse sectional view taken on line 5—5 of Fig. 4.

Fig. 6 is a fragmentary side elevational view showing one of the hoisting units of the apparatus illustrated in Fig. 1, in a position to which it is bodily shifted to obtain a favorable initial mechanical advantage during the first stages of operation of the hoisting unit from its lowermost position.

Fig. 7 is a transverse sectional view taken on the line 6—7 of Fig. 6 and showing the structure on a somewhat larger scale.

Fig. 8 is a longitudinal, vertical sectional view taken on line 8—8 of Fig. 4.

Fig. 9 is a diagrammatic view showing the wire diagram of the control circuit of the power driving mechanism of my improved hoisting apparatus.

In Fig. 1 of the drawings is illustrated hoisting apparatus embodying the invention which comprises hoisting units A and B each of which are substantially identical, the description of one of which will serve, in all but certain respects hereinafter specified, for the others. These hoisting units are particularly constructed to lift vehicles but may be readily adapted to the lifting of numerous other articles. They are preferably operatively mounted on a track comprising spaced rails 10 and 11 of channel shaped cross section having inwardly facing upper flanges 12 and 13 and lower flanges 14 and 15. The rails 10 and 11 may be mounted in a shallow groove formed in a platform structure (not shown) which may be disposed upon a floor structure or they may be mounted in a shallow groove (not shown) of a floor structure with the upper flanges 12 and 13 flush with the floor surface.

The hoisting units A and B each include a

shiftable carriage, generally designated by the numeral 17, having a horizontal base plate 18 and a vertically upstanding flange 19. Provided on each of the opposite ends of the shiftable carriage are wheels 20 and 21 which are received between the flanges 12 and 14 and 13 and 15 of the rails 10 and 11, respectively. The wheels 20 and 21 are journalled on the outer end portions of trunnions 22 and 23, which are respectively mounted on and extend outwardly from the end flanges 24 and 25 of the carriage 17. The end flanges 24 and 25 may be welded to or formed integral with the base plate 18 and flange 19 of the carriage 17.

Each hoisting unit includes a boom member, generally designated by the numeral 29, which comprises a pair of channel members 30 and 31 having outwardly facing web portions and provided with solid lower end portions 30' and 31', respectively. The solid lower end 30' of the channel member 30 is apertured and journalled on the trunnion 22 at a location between the wheel 20 and end flange 24, as shown in Fig. 5. The solid lower end 31' of the channel member 31 is apertured and journalled on the trunnion 23 at a location between the wheel 21 and the end flange 25.

A load receiving seat generally designated by the numeral 36, is pivotally mounted on the upper ends of the channel members 30 and 31 as illustrated in Fig. 1. The load receiving seat 36 comprises a channel bar 37 on the opposite end portions of each of which is shiftably mounted for movement longitudinally and transversely of the bar 37, a rubber pad 38. Provided on the opposite side of the bar 37 are spaced downwardly extending ears 39 for receiving pins 40 by which the seat 36 is pivotally mounted on the upper ends of the channel members 30 and 31. The rubber pads 38 of the hoisting unit A may be notched to receive the rear axle of a vehicle.

When the boom member comprising the channel members 30 and 31 is in its uppermost position, the lower side of the bar 37 seats upon the upper extremities of the channel members. During movement of the boom member 29 from its lower to its upper position the seat 36 is retained in a substantially horizontal position by parallelogram mechanism including link members 41 extending substantially parallel to the channel members 30 and 31 which are pivotally attached at their upper ends by a pin 42 to rigid arms 43 extending from the lower side of the bar 37 of the seat member, as shown in Fig. 1. The lower ends of the links 41 are pivotally attached by pins 44 carried by ears 44' extending leftwardly from the flange portion 18 of the carriage 17. The pivotal axis provided by the pins 42 and 44 are equidistant from the pivotal axis of the seat 36 provided by the pins 40 and the pivotal axis of the boom member provided by the trunnions 22 and 23, respectively. This provides a parallelogram mechanism which retains and supports the seat 36 in horizontal load supporting position during movement of the boom member 29 between its lower and upper positions. When the boom member is in its upright position the seat 36 is supported in horizontal position by engagement of its lower side with the upper extremities of the channel members 30 and 31.

The boom member 29 is supported and guided during its movements by a lever system, generally designated by the numeral 45, which includes a rigid yoke element comprising an intermediate span part 46 and spaced rigidly connected link arms 47. The span part 46 and link arms

47 may be integrally formed, welded or otherwise suitably rigidly connected. The free ends of the link arms 47 are journalled on trunnions 48 fixed to and extending inwardly from the bars 30 and 31 of the boom member 29 at aligned locations intermediate the length of the bars 30 and 31. Provided on the span part 46 of the yoke are spaced bearings 49 on which are journalled the upper end portions of a pair of levers 50. As shown in Fig. 1 the levers 50 are straight throughout the major portions of their length but are provided with slightly upwardly curved upper end portions. The lower ends of the levers 50 are pivotally attached to a cross bar 51 which extends between the rails 10 and 11 of the track structure. This cross bar is provided with upwardly extending shoes 52, one of which is engaged between the flanges 12 and 14 of the rail 10 and the other of which is engaged between the flanges 13 and 15 of the rail 11. The cross bar 51 includes integral upwardly extending pairs of flanges 53 and 54 and a central bearing portion 55 having a bore 56. The lower end of one lever 50 is received between the flanges 53 and pivotally attached thereto by a pin 57 and the lower end of the other lever 50 is received between the flanges 54 and pivotally attached thereto by a pin 58. The cross bar 51 is preferably releasably fixed to the side rails 10 and 11 by pins 59 or other suitable means such as bolts, capscrews and the like. The bars 30 and 31 of the boom 29 are adapted to be received between the shoes 52 and the adjacent flanges 53 and 54 respectively when the hoist is in its lower position.

The hoisting unit B is substantially identical to the hoisting member A and similar parts are designated by the same numeral. However, the lower ends of the levers 50 of the hoisting unit B are pivotally attached to a cross bar 51' which is substantially identical to the cross bar 51 of unit A. Provided on the cross bar 51' are pairs of upstanding flanges 63 and 64. The lower end of one lever 50 is received between the flanges 63 and pivotally attached thereto by a pin 65 and the lower end of the other lever 50 is received between the flanges 64 and pivotally attached thereto by a pin 66. The cross bar 51' has an upstanding side flange 67 extending along its left side, as viewed in Fig. 4, on the left side surface of which is provided spaced pairs of ears 68. Between each pair of ears 68 is pivotally mounted a dog 69 which is engageable between teeth of a rack 70, one of which is stationarily mounted adjacent each rail 10 and 11, respectively. The dogs 69 are connected together by a bar 71 by which they may be simultaneously pivoted out of engagement with the rack 70 when it is desired to release hoisting unit B for movement relative to hoisting unit A. In this way the apparatus may be conditioned for shifting loads of different lengths.

As each boom member 29 approaches its lower position, the links 50 and arms 47 reach the relative positions shown in Fig. 7 and further lowering movement brings these members into approaching alignment. A spring 93' is tensioned during movement of the levers 50 and links 47 towards an aligned condition. This spring serves to shift the levers out of alignment when the boom members are raised.

The driving apparatus by which the boom members 29 of the hoisting units A and B may be simultaneously positively raised and lowered and by which only the boom member of the hoist-

ing unit B may be operated if desired, comprises a pair of aligned screw elements 73 and 74, associated with the hoisting units A and B, respectively. The screw element 73 is journaled at one end in the bore 56 of the bearing portion 55 on the cross member 51 and it is held against axial movement by thrust resisting collars 75 fixed to the screw 73 which engage thrust bearings 76 mounted in opposite extremities of the bearing portion 55. The other end of the screw element 73 is journaled in a bore formed in a cross member 76 which extends between and is fixed to the rails 10 and 11. The screw element 74 is journaled at one end in a bearing 77 mounted on a cross member 78 which connects the rails 10 and 11 and at its other end in a bearing 79 mounted on a cross member 80 which joins the right end portions of the rails 10 and 11.

The adjacent ends of the screw elements 73 and 74 are disengageably connected together by a clutch, generally designated by the numeral 81, which includes a clutch element 82 fixed to the right end of the screw element 73, as viewed in Figs. 1 and 4, and a shiftable clutch element 83 which is splined on the left end of the screw element 74. The clutch element 83 is provided with an operating lever 84 which is pivotally mounted at 85 on the rail 10 and operatively connected at its intermediate portion to the clutch element 83. The intermediate portion of the lever 84 is enlarged and provided with an opening in which the right end portion of the clutch element is received. The lever 84 is pivotally connected with a slit ring 84' seated in a groove 85' formed in the clutch element 83, by pins 86' which loosely fits in apertures formed in the lever 84. The free end of the lever 84 extends through a slot in the rail 11 and may be rotated manually in a clockwise direction, as viewed in Fig. 4, to engage the clutch elements 82 and 83 and in a counterclockwise direction to disengage them. The carriage 17 of each hoisting unit A and B, respectively, is provided with a nut member 86 in which one of the screw elements 73 and 74 are threaded.

The screw elements 73 and 74 may be driven in respectively opposite directions by a reversible motor 87 which is drivingly connected with the right end of the screw element 74, as viewed in Fig. 1, by a chain 88 which is engaged on a sprocket 88' fixed to the screw 74 and on a sprocket 89 fixed on the shaft of the motor. The motor 87 is provided with a control circuit, shown in Fig. 9 in which is included a portable switch box, generally designated in Fig. 1 by the numeral 90. The control circuit includes a 110 volt supply circuit comprising conductors 91 and 92, of which conductor 91 is connected to directly to terminals 93 and 94 of a pair of push button switches generally designated 95 and 96, respectively. The switch 95 when closed produces upward movement of the boom members 29 and the switch 96 produces downward movement thereof in a manner hereinafter more clearly set forth. The switch 96 has a terminal 97 which is connected by a conductor 98 with a movable contact element 99 of a limit switch, generally designated by the numeral 100, which is also designated by the legend "Limit Switch Stop Down." The movable contact 99 of this limit switch is preferably pivotally mounted at its right end and yieldably urged by a spring 101 in a counterclockwise direction. The movable contact element 99 of the limit switch 100 is alternatively engageable with terminals 102 and

103. The spring 101 normally urges the movable contact element 99 of the switch 100 into engagement with the terminal 103 but as shown in Fig. 9, the movable contact element 99 is adapted to be engaged with the terminal 102 by a cam 104 which engages a follower 105 attached to the movable contact element 99. The terminal 102 of the limit switch 100 is connected by a conductor 106 and 107 with one terminal of a signal such as a bell 108 and the other terminal of the bell is connected with the conductor 92 of the power supply line. The terminal 103 of the limit switch 100 is connected by a conductor 109 with a relay 110 that establishes rotation of the motor 87 in a direction to produce downward movement of the boom members 29.

As illustrated in Figs. 1 and 4, the limit switch 100 is located on the rail 10, with its follower 105 arranged to be engaged by the cam 104 which is carried by the carriage 17, when the boom member 29 of hoisting unit A is in its predetermined lowermost position. As long as the push button switch 96 is depressed and the movable contact 99 is engaged with the fixed terminal 103, the relay 110 is energized to maintain the motor 87 in operation to drive the boom members downwardly. When the movable contact 99 is disengaged from the terminal 103 and shifted into contact with the terminal 102 by the cam 104, downward drive of the boom members by the motor is discontinued and the bell 108 rings to warn the operator that the boom members are down and to advise him to discontinue depression of the push button switch 96. The boom members may be stopped in any position between their upper and lower positions by merely releasing the push button switch 96.

Hoisting unit A, is also provided with an up limit switch, generally designated by the numeral 111, which includes a movable contact element 112, fixed terminals 113 and 114 and a cam follower 115. The up limit switch 111 is mounted on the rail 10 on the left side of the carriage 17 which is provided with a leftwardly extending cam 116. The movable contact element 112 is normally yieldably urged into engagement with the terminal 114 by a spring 117. The terminal 114 is connected by a conductor 118 to a relay 119 which produces driving of the motor 87 in an opposite direction to that produced by the relay 110 in order to drive the boom members upwardly. When the push button switch 95 is closed, current is supplied from its terminal 120 through a conductor 121, movable contact element 112, terminal 114 and conductor 118 to the relay 119 which establishes upward driving of the boom members 29 by the motor 87. When the boom member 29 of hoisting unit A reaches a predetermined upper position the cam 116 engages the follower 115 and rotates the movable contact element out of engagement with the terminal 114 and into engagement with the terminal 113 which is connected with conductors 106 and 107 leading to the signal 108. This action thus discontinues upward driving of the boom members 29 and actuates the signal 108 to advise the operator that the boom members are in their upper positions. The up push button 95 may be released at any time during upward movement of the boom members to discontinue such upward movement at any selected elevation of the boom members.

The cam 104 which operates the down limit switch 100 may be rendered inoperative to shift

the movable contact element 99 from engagement with the fixed terminal 103 into engagement with the fixed terminal 102, by an arm 122 rigid with lever 84 which is shown in Figs. 4 and 9. The arm 122 is arranged to engage the cam 104 when the lever 84 is rotated in counterclockwise direction and to deflect it away from the follower 105 as such rotation of the lever 84 disengages the clutch elements 82 and 83. Therefore, when these clutch elements are disengaged the limit switch 100 is always set to allow its movable contact element 99 to remain in contact with the terminal 103 even though the boom member 29 of hoisting unit A is in its lowermost position. When the boom member of hoisting unit A is in any position below its upper predetermined position the movable contact element 112 of the limit switch 111 is in the position shown in Fig. 9, and thus, while these conditions exist and while the clutch 81 is disengaged the push buttons 95 and 96 can be utilized to produce up and down movements of only the boom member of the hoisting unit B.

While both of the boom members of the hoisting units A and B are in their lower positions, and the clutch 81 is disengaged and the cam 104 is held in an inoperative position, the rotation of the screw element 74 in respectively opposite directions under the control of the push buttons 95 and 96 may be relied upon to drivingly shift the hoisting unit B in correspondingly opposite directions relative to the hoisting unit A. This is accomplished by lifting the bar 71 and associated dogs 69 and holding the latter out of engagement with the teeth of the rack 70 while adjustment of the hoisting unit B is produced.

The boom members of the two hoisting units may be simultaneously operated by simple driving mechanism of inexpensive constructions which can be conveniently conditioned with the aid of a common clutch to operate only one hoisting unit. The same driving mechanism can be utilized to drivingly shift one hoisting unit relative to the other and the limit switch control mechanism and signal, which saves the operator from closely watching the actions of two hoists, is automatically conditioned, when the clutch of the driving mechanism is disengaged, to allow one screw element to either raise and lower one boom member or to shift one hoisting unit relative to the other.

Although but one specific embodiment of the invention is herein shown and described, it will be understood that various changes in the details and construction thereof may be made without departing from the spirit and scope of my invention.

I claim:

1. Vehicle hoisting apparatus including a support, a pair of hoisting units mounted on said support, each including a boom member shiftable between upper and lower positions, means for drivingly shifting said boom members including a pair of screw elements each operatively connected with one of said boom members respectively, a releasable clutch for selectively connecting and disconnecting said screw elements to permit simultaneous shifting of said boom members and shifting of only one thereof respectively, and manually operable control mechanism for selectively engaging and disengaging said clutch.

2. Vehicle hoisting apparatus including a support, a pair of hoisting units mounted on said support, each including a boom member shiftable between upper and lower positions, a thread-

ed nut element on each of said hoisting units respectively, means for drivingly shifting said boom members including a pair of screw elements each independently rotatably mounted on said support in permanently threaded engagement with one of said nut elements respectively, one end of each of said screw elements being adjacent each other, a releasable clutch for selectively connecting and disconnecting the adjacent ends of said screw elements to permit simultaneous shifting of said boom members and shifting of only one thereof respectively, manually operable control mechanism for selectively engaging and disengaging said clutch, and power driving mechanism operatively connected with one of said screw elements.

3. Vehicle hoisting apparatus including a support, first and second hoisting units mounted on said support in spaced relation with respect to each other, each including a boom member shiftable between upper and lower positions, a first screw rotatably mounted on said support and threadedly connected with the boom member of said first hoisting unit, mechanism for drivingly rotating said first screw element, a second screw rotatably mounted on said support in substantially axial alignment with said first screw and threadedly connected with the boom member of said second hoisting unit, means bodily shiftably mounting said first hoisting unit on said support for bodily movement relative to said second hoisting unit and longitudinally relative to said support and screw, releasable anchoring means coacting between said support and said first hoisting unit for fixing said first hoisting unit in selected positions relative to said second hoisting unit to accommodate lifting of vehicles of different lengths, and a releasable clutch for positively connecting together the adjacent ends of said aligned screw.

4. Vehicle hoisting apparatus including a support, first and second hoisting units mounted on said support in spaced relation with respect to each other, each including a boom member shiftable between upper and lower positions, a first screw rotatably mounted on said support and threadedly connected with the boom member of said first hoisting unit, mechanism for drivingly rotating said first screw element, a second screw rotatably mounted on said support in substantially axial alignment with said first screw and threadedly connected with the boom member of said second hoisting unit, means bodily shiftably mounting said first hoisting unit on said support for bodily movement relative to said support and screws and said second hoisting unit, releasable anchoring means coacting between said support and said first hoisting unit for fixing said first hoisting unit in selected positions relative to said second hoisting unit to accommodate lifting of vehicles of different lengths, and means for selectively drivingly connecting and disconnecting the adjacent ends of said screws for simultaneously operating both of said screws and only said first screw respectively, said first hoisting unit being bodily shiftable relative to said screws and said support by said first screw when said screws are disconnected and said anchoring means are released.

5. Vehicle hoisting apparatus including a support, a pair of hoisting units mounted on said support, each including a boom member shiftable between upper and lower positions, means for drivingly shifting said boom members between said upper and lower positions including a pair of series related actuating elements one opera-

tively connected with each of said boom members respectively, a power driving mechanism operatively connected with one of said actuating elements for impelling the latter, a releasable clutch for selectively connecting and disconnecting said actuating elements for operating both of said boom members simultaneously and operating only one of said boom members respectively, and manually operable control mechanism for selectively engaging and disengaging said clutch.

6. Vehicle hoisting apparatus comprising a base structure, a pair of boom members mounted on said base structure in spaced relationship for shifting movement between generally vertical and generally horizontal positions, mechanism associated with each of said boom members for shifting it between said positions including a lever element and a link element pivoted at one end to said lever element and pivoted at its opposite end to said boom member, means for relatively shifting each boom member and the other end of each lever element in opposite directions for respectively raising and lowering said boom member through the action of said link and lever elements, said means including a pair of series related actuating elements one for shifting each of said boom members respectively, and a releasable clutch for selectively connecting and disconnecting said actuating elements to operate both of said boom members simultaneously and to operate only one of said boom members respectively.

7. Vehicle hoisting apparatus comprising a base structure, a pair of boom members mounted on said base structure in spaced relationship for shifting movement between generally vertical and generally horizontal positions, mechanism associated with each of said boom members for shifting it between said positions including a lever element and a link element pivoted at one end to said lever element and pivoted at its opposite end to said boom member, means for relatively shifting each boom member and the other end of each lever element in opposite directions for respectively raising and lowering said boom member through the action of said link and lever elements, said means including a pair of series related actuating elements one for shifting each of said boom members respectively, and a releasable clutch for selectively connecting and disconnecting said actuating elements to operate both of said boom members simultaneously and to operate only one of said boom members respectively, said actuating elements each including a screw and means threadedly connecting it with one of said boom members respectively.

8. Vehicle hoisting apparatus comprising a base structure, a pair of boom members mounted on said base structure in spaced relationship for shifting movement between generally vertical and generally horizontal positions, mechanism associated with each of said boom members for shifting it between said positions including a lever element and a link element pivoted at one end to said lever element and pivoted at its opposite end to said boom member, means for relatively shifting each boom member and the other end of each lever element in opposite directions for respectively raising and lowering said boom member through the action of said link and lever elements, said means including a pair of series related screw elements rotatably mounted on said base structure and a pair of nut elements, each in permanently threaded engagement with one of said screw elements respectively and each mounted on an end of one boom member,

apparatus for drivingly rotating one of said screw elements in respectively opposite directions, and a releasable clutch element for selectively connecting and disconnecting said screw elements to operate both of said boom members simultaneously and to operate only one of said boom members respectively.

9. Vehicle hoisting apparatus including a support, first and second hoisting units mounted on said support, each including a boom member shiftable between upper and lower positions, means for drivingly shifting said boom members including aligned first and second screw elements mounted on said support for rotation about a substantially common axis and operatively connected with the boom members of said first and second hoisting units respectively, a reversible electric motor drivingly connected with said first screw element, a control circuit for said electric motor including limit switch means responsive to downward movement of the boom member of said second hoisting unit to a predetermined position for interrupting operation of said electric motor, a releasable clutch for selectively connecting and disconnecting said screw elements, and a control member for said clutch including an element for operating upon said limit switch means to render it ineffective to interrupt operation of said motor when said clutch is conditioned to disconnect said screw elements.

10. Vehicle hoisting apparatus including a track, a first hoisting unit shiftably mounted on said track, a second hoisting unit mounted on said track in spaced relation to said first hoisting unit, anchor means for releasably fixing said first hoisting unit in a selected position relative to said second hoisting unit, each of said hoisting units including a boom member shiftable between upper and lower positions, means for drivingly shifting said boom members between said upper and lower positions including first and second screw elements threadedly connected with the boom members of said first and second hoisting units respectively, a reversible electric motor drivingly connected with said first screw element, a control circuit for said electric motor including means for selectively operating said motor in respectively opposite directions, limit switch means in said circuit responsive to downward movement of the boom member of said second hoisting unit to a predetermined lower position for interrupting operation of said motor, a releasable clutch for connecting and disconnecting said screw elements, and a control member for said clutch including an element engageable with said limit switch means for rendering it ineffective to interrupt operation of said motor when said clutch is disengaged, said first screw element being operable by said motor to drivingly shift said first hoisting unit longitudinally of said track and relative to said second hoisting unit when said clutch is disengaged and said anchor means is released.

11. Vehicle hoisting apparatus comprising first and second hoisting units each including a boom member shiftable between upper and lower positions respectively, mechanism for selectively simultaneously shifting both of said boom members and only the boom member of one of said units respectively between said positions including an actuating member for each of said boom members and means for selectively connecting and disconnecting said actuating members, reversible power driving mechanism drivingly connected with one of said actuating members, an electrical control circuit for selectively operat-

ing said power driving mechanism in forward and reverse directions to respectively raise and lower said boom members, limit switch means in said circuit responsive to downward movement of one of said boom members for interrupting reverse drive of said driving mechanism, and a control member for said connecting and disconnecting means including an element for rendering said limit switch means inoperative to interrupt reverse operation of said driving mechanism when said control member is shifted to disconnect said actuating members.

12. Vehicle hoisting apparatus comprising a base structure, a pair of boom members mounted on said base structure in spaced relationship for shifting movement between generally vertical and generally horizontal positions, mechanism associated with each of said boom members for shifting it between said positions including a lever element having an end operatively connected with said boom member, and mechanism for relatively shifting each boom member and the other end of each lever element for respectively raising and lowering said boom member through the action of said lever member including a pair of driving members and means for permanently operatively connecting each of said boom members with one of said driving members respectively and connecting means between said driving members including a releasable element for selectively connecting and disconnecting said driving members to operate both of said boom members simultaneously and to operate only one of said boom members respectively.

13. Vehicle hoisting apparatus comprising a base structure, a pair of boom members mounted on said base structure in spaced relationship

for shifting movement between generally vertical and generally horizontal positions, mechanism associated with each of said boom members for shifting it between said positions including a lever element and means operatively connecting one end of said lever element to said boom member, means for relatively shifting each boom member and the other end of each lever element in opposite directions for respectively raising and lowering said boom member through the action of said lever elements, said means including a pair of series related actuating elements one for shifting each of said boom members respectively, and a releasable clutch for selectively connecting and disconnecting said actuating elements to operate both of said boom members simultaneously and to operate only one of said boom members respectively.

DAVID A. WALLACE.
